CONSOLE STEREO CABINET

Falkon S. Davis, 209 Sawmill Drive W.,
Berkeley Heights, N.J. 07922

Filed Feb. 21, 1974, Ser. No. 444,470

Int. Cl. D14—03

U.S. Cl. D56—4 C

FIG. 1 is a front, top and right side perspective view of a console stereo cabinet showing my new design; and FIG. 2 is a rear, bottom and left side perspective view.

The pattern partially shown within the four equal divisions of the front of the cabinet is continuous within these areas.

I claim:

The ornamental design for a console stereo cabinet, substantially as shown and described.
